UNITED STATES PATENT OFFICE.

WILLIAM EDWIN WOLFE, OF WILDER, VIRGINIA, ASSIGNOR TO CLINCHFIELD COAL CORPORATION, OF DANTE, VIRGINIA, A CORPORATION OF VIRGINIA.

GATHERING-REEL MOUNTING FOR MINE LOCOMOTIVES.

1,409,328.

Specification of Letters Patent. Patented Mar. 14, 1922.

Application filed March 18, 1920. Serial No. 366,936.

To all whom it may concern:

Be it known that I, WILLIAM E. WOLFE, a citizen of the United States, residing at Wilder, in the county of Russell and State 5 of Virginia, have invented a new and useful Gathering-Reel Mounting for Mine Locomotives, of which the following is a specification.

This invention has reference to gathering 10 reel mountings for mine locomotives and its object is to provide for the active propulsion of the gathering reel without the necessity of a separate motor for the purpose and without liability of damage to the cable 15 wound on the reel, and furthermore to reduce wear upon the parts.

In accordance with the invention, the mine 20 locomotive is provided with a power electric motor whereby the locomotive may be driven from place to place, as desired. Moreover, the locomotive is provided with a gathering reel for the cable furnishing the power motor with current. Such arrangements are common in mine locomotives and so need no particular illustration or description. As heretofore constructed, the gathering reel has 25 been power driven mechanically by gearing connections with the power motor used for propelling the locomotive, or has been furnished with a separate electric motor. In 30 the case of a mechanical drive between the power motor and the reel, the mechanism has been of a more or less complicated nature and the arrangement has been such that 35 a considerable portion of the mechanism has been constantly driven while the locomotive is in service, thus contributing to wear and to first cost and maintenance costs. In the case of a separate electrical drive for the 40 gathering reel, additional complications are introduced, the first cost of the installation is materially increased, and operating troubles are multiplied. Oftentimes the heavy demand of the power motor for current 45 will rob the smaller reel driving motor and thus cause sagging of the cable because the power of the small motor is reduced and the cable is not taken up fast enough, for which reason the cable may be run over and 50 injured by the locomotive. Again, in the case of a separate electric motor for driving the reel there are added many points of wear, such as the brushes, the commutator, the numerous bearings and also the liability 55 of burnouts.

While the objections to the electrical driving of the reel are in a measure overcome by other mechanical drives which have been proposed, the invention so reduces the cost of construction of the mechanical drive as 60 to present advantages over other mechanical drives.

In accordance with the invention there is provided an intermediate shaft which is at 65 all times still except when the reel is being positively rotated to wind the cable thereon. Flexibility of drive between the power motor and the intermediate shaft is obtained by a sprocket connection, one member of which is mounted directly on the axle or motor 70 armature shaft, and the other member of which is loosely mounted on the intermediate shaft, and represents the only part of the whole reel drive which moves, and is therefore subject to wear, when the locomotive 75 is moving but the reel is not being driven. Moreover, provision is made for the renewal of parts, should any accident occur while the locomotive is in the mine and despite the close quarters in which the locomotive is 80 necessarily located, thereby saving the necessity of moving the locomotive from the point where damage may have occurred to a central point where a shop is located.

The invention will be best understood 85 from a consideration of the following detailed description taken in connection with the accompanying drawings forming part of this specification, with the understanding, however, that the invention is not confined 90 to any strict conformity with the showing in the drawings, but may be changed and modified so long as such changes and modifications mark no material departure from the salient features of the invention as expressed 95 in the appended claims.

In the drawings,

Fig. 1 is an elevation, with some parts in section, showing so much of a mine locomotive, with the invention applied, as is 100 necessary for an understanding of the invention.

Fig. 2 is a plan view of a portion of the structure shown in Fig. 1 and omitting the reel.

Fig. 3 is a longitudinal axial section of the intermediate or auxiliary shaft and some adjacent parts.

Referring to the drawings, there is shown a portion of the casing of a mine locomotive 110

1 and also a driving axle 2 and supporting wheels 3 also forming part of the locomotive. The axle 2 is indicated as carrying a gear wheel 3^a engaged by a pinion 4 mounted on 5 the shaft 5 which may be taken as indicative of the armature shaft of an electric motor simply indicated at 5^a in Fig. 2, the whole showing being more or less in the nature of a diagram, for no attempt is made to show 10 these parts with any accuracy since they constitute in themselves no part of the invention and may be considered as common to mine locomotives.

Secured in the frame of the locomotive 1 15 are journal bearings 6 each provided with a removable cap 7 suitably alined to receive and support a counter or intermediate shaft 8, the caps 7 being held in place by bolts 7^a, so that on the removal of a minimum number 20 of bolts the shaft 8 and parts carried thereby may be readily removed from the locomotive and replaced by another shaft, with the parts belonging thereto, thus making it possible to install repairs or replacements without the 25 necessity of moving the mine locomotive to a repair shop. This is advantageous in that the intermediate shaft, which is the part most liable to wear or damage, may be replaced in so short a time, say about half an 30 hour, that the delay caused by such replacement is practically negligible. Ordinarily breakdowns in mine locomotives mean the taking of the locomotive to a repair shop and the putting out of service of not only the 35 damaged locomotive and perhaps other locomotives, but practically a large section of the mine force, so that the loss in time means a very material loss to the mine and to the workmen, all of which is practically obviated 40 by the invention in providing a structure of small liability to breakdowns, as compared with other installations, and one which may be very readily restored to working conditions with so small a delay in restoring 45 working conditions as to be, from all practical considerations, negligible.

Fast to the shaft 8 there is a sprocket pinion 9, and fast to the shaft 2 is a sprocket wheel 10, the wheel and pinion being connected 50 by a sprocket chain 11 whereby to form a flexible drive between the shaft 2, which may be considered as the power shaft of the locomotive, and the intermediate or countershaft 8.

55 Mounted on the shaft 8 is an elongated sleeve 12 capable of being moved lengthwise of the shaft and constrained to rotate with the shaft 8 by an intermediate key or spline 13.

60 The pinion 9 and sleeve 12 are provided with one-way clutch members 14, 15, respectively. The clutch member 14 may be conveniently formed as a part of the hub of the pinion 9 and the clutch member 15 may be 65 conveniently formed as a portion of one end

of the sleeve 12. The longitudinal movement of the clutch member 15, together with the sleeve 12, lengthwise of the shaft 8, may be brought about by an actuating fork 16 on one end of an arm or lever 17 and engaging 70 in a groove 18 in the clutch member 15. This permits the movement of the two clutch members into and out of engagement. These clutch members are provided with teeth 19 having abrupt shoulders 20 and spiral walls 75 21 so as to produce positive engagement in one direction and cam or spiral engagement in the other direction, tending to separate the clutch members. The arrangement is such that on movement in one direction the 80 clutch is positively acting, but will automatically separate on the movement of the clutch member 14 in the opposite direction.

Carried on top of the locomotive frame 1 85 is a pedestal 22 through which there extends an upright shaft 23 carrying at the lower end a bevel gear wheel 24 in the path of a bevel pinion 25 keyed to the sleeve 12 so as to participate in the sliding movements thereof. The shaft 23 rises through and 90 above the top of the pedestal 22, and at the upper end the shaft 23 is screw threaded, as shown at 24^a, with a nut 25^a applied to the screw threaded end. Surrounding the shaft 23 below the nut 25 is a spring 26. 95

On top of the pedestal 22 is a bearing or friction plate 27 in which there is formed a groove for the reception of a friction ring 28 shown as rectangular in cross section, although not necessarily of such particular shape. 100

The shaft 23 rises through the friction plate or disk 27, which is keyed to the shaft 23 and revolves on top of the pedestal 22. On the friction ring 28, there is a friction plate 29 carrying a gathering reel 30 fast to the plate 29 by bolts 31 or in any other suitable manner. The spring 26 surrounds the upper end of the shaft 23 and bears on the reel 30, so that the plates 27 and 29 are 110 in frictional engagement through the friction ring 28, wherefore there is provided friction-overload-slip means causing the reel to be constrained to rotate with the shaft 23, except when the resistance to such rotation becomes greater than the holding power of the friction means, as determined by the action of the spring 26 and friction ring 28. 115

If the locomotive be traveling under power delivered by the locomotive motor to the 120 wheels 3, and the clutch members 14 and 15 be disengaged, the axle or shaft 2, and also the motor and the clutch member 14 connected by the chain 11 to the axle 2, are the only rotating parts and consequently the only 125 parts liable to wear. When the cable carried by the reel 30 is being paid out therefrom the reel idly rotates, although this rotation is not a free rotation, because of the friction established by the friction ring 28 130

and the nut 25, together with the spring 26. When it becomes necessary to wind the cable onto the reel, the lever 17 is manipulated to couple the two members 14 and 15 of the 5 clutch together. The movement of the clutch member 15 into engagement with the clutch member 14 connects the sleeve 12 to the source of power and at the same time the pinion 25 is moved into mesh with the gear 10 wheel 24, setting the reel 30 in motion in the proper direction to wind the cable on the reel.

When the reel is being driven by power to wind the cable thereon, the power is that 15 furnished by the driving motor of the locomotive, and consequently there can be no variation in the reel speed with respect to the speed of travel of the locomotive. For this reason, there is no danger of slackening 20 of the reel cable while being wound up and of the locomotive running over and damaging it.

When it becomes necessary, from one cause or another, to replace the shaft 8 or parts 25 carried thereby, or other parts liable to wear, because of the peculiar duties to which a mine locomotive is put, the removal of four bolts 7^a is sufficient to permit taking out the shaft 8 and installing a new shaft in its 30 place. Because of the simplicity of structure, this may be done where the locomotive may happen to be located in the mine and with but a minimum of delay, so that the locomotive need not be moved to some re- 35 pair point, but may in most cases, be thoroughly repaired, by replacements or otherwise, in the confines of the mine and thus avoiding the laying off of the men and the delaying of the working of the mine for a 40 material period of time.

What is claimed is:

1. A mine locomotive comprising a body structure, an axle, drive wheels thereon, a countershaft adjacent to and parallel with the axle, flexible connections between the axle and countershaft, a sleeve slidable on and rotatable with the countershaft, a gear element on one end of the sleeve, a clutch on the other end of the sleeve, a one-way clutch 45 member on the countershaft for coupling the sleeve to and uncoupling it from the axle, another shaft, separable gearing therefor operable by the sleeve, a winding drum on the last-named shaft, and friction means 50 providing slippage due to the drive of the winding drum.

2. In a mine locomotive, a gathering reel, connections between the motor of the locomotive and the gathering reel including friction 55 overload slip means comprising a carrying shaft for the gathering reel, friction

members, and a slip member in engagement with the rotatable friction members and engaged thereby, said friction members having associated therewith manually operable controlling means for varying the degree of frictional engagement between said friction members.

3. In a mine locomotive, a gathering reel, a countershaft separate from the reel, a flexible driving connection between the motor of the locomotive and the countershaft and including a one-way clutch, a sleeve on the countershaft, movable longitudinally of the latter and including the other member of the clutch, separable gearing between the sleeve and the gathering reel, with one member of the gearing on and movable with the sleeve, said gearing including coacting friction slip means yieldable to overload conditions, and manipulating means for the sleeve to simultaneously control the clutch and gear members of the sleeve.

4. In a mine locomotive having a counter shaft, a longitudinally movable sleeve on the counter shaft having a clutch member at one end and a bevel pinion at the other end, another clutch member on and rotatably independent of the shaft, a flexible connection between the second named clutch member and the power side of the locomotive, a bevel gear wheel into and out of mesh with which the bevel pinion on the sleeve is movable, and a gathering reel connection to the bevel gear wheel for rotation thereby, and means under 85 the control of an operator for shifting the sleeve along the counter shaft to simultaneously couple the clutch and move the bevel pinion into mesh with the bevel gear wheel. 90 or to simultaneously disconnect the clutch 95 members and the bevel pinion and gear wheel.

5. A mine locomotive provided with a drive axle, a countershaft parallel therewith, a sleeve mounted on and movable longitudinally of the countershaft, a clutch member on one end of the sleeve, a pinion on the other end of the sleeve, a companion clutch member on the countershaft in position to be connected to the first-named clutch member, a gathering reel, an upright shaft mounted on the locomotive and carrying the gathering reel, a gear wheel connected to the upright shaft to drive it, and means for shifting the longitudinally movable sleeve 105 on the countershaft to simultaneously connect or disconnect the clutch members and gears.

In testimony that I claim the foregoing as my own, I have hereto affixed my signature.

WILLIAM EDWIN WOLFE.
